UNITED STATES PATENT OFFICE.

SIDNEY R. HARRINGTON, OF NEW TORONTO, ONTARIO, CANADA, ASSIGNOR TO THE GOODYEAR TIRE & RUBBER COMPANY, OF AKRON, OHIO, A CORPORATION OF OHIO.

TUBE-DEFLATING STAND.

Application filed October 26, 1926. Serial No. 144,275.

My invention relates to apparatus designed for the purpose of deflating inner tubes, and it has particular relation to the tube supporting and operating elements of 5 such apparatus.

One object of my invention is to provide an apparatus particularly adapted to deflate inner tubes which have been cured in a mold or upon curved or circular mandrels.

10 Another object of my invention is to provide an apparatus which is adapted to deflate inner tubes without subjecting them to undue distortion and without wrinkling them.

15 In the manufacture of inner tubes for pneumatic automobile tires, it has been customary to inflate them in order that they may be tested properly by submerging them in a liquid bath. After the testing operation 20 has been completed, it is necessary to deflate the tubes before they can properly be folded and packed preparatory to shipment thereof.

25 Heretofore apparatus have been constructed which were provided with complementary U-shaped supports formed from sheet metal material and which were adapted to be moved toward and away from each other to stretch and deflate inner tubes mounted thereon. Suitable conduits communicating with vacuum apparatus were 30 also provided and were adapted to be connected to the valve stem of the inner tube to facilitate the deflation of the tube. It has been found that apparatus of this sort are 35 not well-adapted to be employed for the purpose of deflating inner tubes which have been cured upon curved or circular mandrels, because of the peculiar characteristics of this type of tube, and because of the fact 40 that the valve stem is offset from the plane of the angular tube.

45 By employing a device provided with relatively movable parts formed with cone-shaped converging tube supporting surfaces 50 designed according to my invention, an inner tube is mounted upon the converging surfaces, and when the relatively movable parts are actuated away from each other the tube rolls slightly down the incline of the converging surfaces. This operation causes 55 the valve stem which is disposed within an opening in one of the tube supports, to be centered properly, and at the same time the rolling action of the tube prevents wrinkling thereof.

For a better understanding of my invention, reference may now be had to the accompanying drawings forming a part of this specification, of which:

Fig. 1 is a front elevational view of a 60 tube deflating apparatus constructed according to my invention;

Fig. 2 is a side elevational view of the apparatus shown in Fig. 1, parts thereof being broken away for the sake of clearness; 65

Fig. 3 is a fragmentary perspective view of an inner tube which has been cured upon a curved or circular mandrel and illustrating the position of the valve stem thereof.

Fig. 4 is a cross-sectional view on a larger 70 scale of a portion of the device embodying my invention and illustrating the position of an inner tube mounted thereon incident to its deflation.

Fig. 5 is a fragmentary cross sectional 75 view similar to and taken at right angles to the view shown in Fig. 4; and,

Fig. 6 is a fragmentary cross sectional view of a valve spacing portion of the device embodying my invention, the view being 80 taken substantially along the line VI—VI of Fig. 2.

In practicing my invention, I provide a frame construction 10 having a bracket 11 bolted thereto which supports an outwardly 85 extending and downwardly sloping arm 12. A tube supporting member or holder, generally indicated by the numeral 13, constituting one of the main features of my invention, comprises an inverted U-shaped tube 90 support 14, which is bolted to the arm 12 and which is provided with a conical or converging outer surface 15, the angle of convergence being about 12°. Additional bracing bars 16 rigidly secured to the frame 10 95 and to the inverted U-shaped support 14 maintain the latter in a definite stationary position.

A second U-shaped member 17, composed 100 of sheet material and provided with a conical or converging surface 18 forming substantially a continuation of the surface 15, is disposed immediately below the inverted U-shaped member 14 and is vertically movable toward and away from the latter. The 105 movable U-shaped member 17 is provided with laterally extending braces 19 rigidly secured thereto and rigidly secured to a fluid actuated cylinder 20 mounted upon a piston rod 22. This piston rod is secured at its 110

upper end to the bracket 11 and at its lower end to a similarly disposed bracket 23, these brackets being rigidly secured to the frame 10. A piston head 24 which is normally positioned centrally within the cylinder 20 is rigidly secured to the rod 22. By admitting fluid under pressure through a conduit 25 at the lower portion of the cylinder, the latter, together with the U-shaped member, is moved downwardly, the approximate lower position of the U-shaped member being indicated by dot and dash lines 26. Likewise, the cylinder 20, together with the U-shaped member 17, is moved upwardly by admitting fluid under pressure through a flexible conduit 27 disposed at the upper portion of the cylinder 20. Additional flexible valve controlled conduits 28 and 29 are provided for the purpose of permitting fluid to escape from the cylinder after the latter has been actuated in one or the other of the directions indicated.

Downward movement of the cylinder can be limited by employing a latch 30 slidably and rotatably mounted upon a rod 32 and provided with a laterally extending lug 33, which is adapted to be vertically adjustable within notches 34 formed in a flange 35 of the frame. The rod 32 is secured at its ends by means of brackets 36 and 37 bolted to the frame 10. For the sake of convenience, I have provided a handle 38 for the latch which facilitates vertical adjustment thereof within the notches.

The upper stationary U-shaped member 14 supports a two-way valve mechanism 39 rigidly secured thereto by means of a bracket 40. Two fluid conveying conduits 42 and 43 connected to the valve 39 communicate with a vacuum apparatus (not shown) and with the atmosphere respectively, the valve being operated by means of a handle 44.

As best shown in Figs. 2 and 4, a relatively short flexible conduit hose 45 is connected to the valve mechanism 39 and is provided with a nozzle 46, adapted to fit over and open the end of a valve stem 47, which is connected to an inner tube 48. The inner tube is mounted upon the support 13 and by operating the handle 44, the vacuum apparatus exhausts air from the tube.

In Fig. 3, I have illustrated a portion of an inner tube 48 cured on a curved mandrel. In this type of inner tube, the valve stem 47 is offset from the line defining the shorter or inner circumference of the tube as shown. The reason for so offsetting the valve stem is that in this position it facilitates the folding of the inner tube and the packing thereof in cartons. In order to properly position and hold the valve stem upon the support 14, an opening 49, shown in Figs. 4, 5 and 6, is provided therein, one side of which is irregular and forms a notch 50. An opening of this shape in the sheet material of

the support provides corners or edges 52 and 53 which are bent inwardly and are adapted to engage flanges 54 of a conventional valve spacer 55 of the stem. Thus, the portion of the inner tube adjacent the valve stem is drawn inwardly from the surrounding surface of the tube support and the valve is held firmly by the wedging action of the valve spacer 55 between the edges 52 and 53.

The inner tube 48, shown in full lines of Fig. 4, is in proper position for deflation thereof. In looping the tube about the support, it will be observed that a portion thereof will be slightly twisted in order to position the offset valve stem within the notch 50. As soon as the nozzle 46 is connected to the valve stem 47 and the valve mechanism 39 is operated to exhaust air from the inner tube, fluid under pressure is admitted to the lower portion of the cylinder through the conduit connection 25. The cylinder 20 will then be actuated downwardly thereby actuating the support 17 in the same direction and stretching the inner tube immediately before and during the deflation thereof. The conical or converging walls 15 and 18 of the tube support 13 cause the inner tube to roll slightly while it is being deflated. Upon completion of the deflating operation the inner tube assumes the position shown in dot and dash lines of Fig. 4, and in this position, the valve stem is properly centered. This operation also prevents the inner tube from being wrinkled and from being subjected to injurious distortion as well as compensating for the twisting of the inner tube which occurs incidentally to the positioning of the valve stem within the opening 49. After the air has been exhausted from the inner tube, the cylinder 20 is actuated upwardly and the deflated tube removed from the support.

From the foregoing description, it will be apparent that a device embodying my invention greatly facilitates the deflation of inner tubes and that the simplicity of its construction, as well as its peculiar mode of operation, renders it particularly well-adapted for use in deflating all inner tubes cured in molds or upon curved or circular mandrels.

Although I have illustrated but one form which my invention may assume and described in detail but a single application thereof, it will be apparent to those skilled in the art that it is not so limited but that various minor modifications and changes may be made therein without departing from the spirit of the invention or from the scope of the appended claims.

What I claim is:

1. An inner tube deflating device comprising an expansible holder provided with conical inner tube supporting surfaces.

2. An inner tube deflating device comprising an expansible holder including telescoping sections provided with converging working supporting walls and means to actuate the sections. 5
3. An inner tube deflating device comprising a frame, a pair of telescoping U-shaped sections carried by the frame and provided with converging peripheral surfaces and 10 means to actuate the sections.
4. A device for deflating an inner tube having a valve stem therein comprising an expansible holder provided with a conical surface adapted to support circumferentially 15 the inner tube, said holder including integral means for positively engaging the valve stem to separate a portion of the stem from the wall of the inner tube opposite the connection of the valve stem.
5. A device for deflating an inner tube having a valve stem therein comprising an upper section provided with converging peripheral surfaces and a lower section movable toward and away from the upper section, the upper section being provided with 20 an opening for receiving the valve stem, the material surrounding the opening being bent to form inwardly projecting edges adapted to engage the stem to space it from the wall of the inner tube opposite the valve stem 30 connection.
6. A deflating device comprising a frame, an inverted U-shaped section provided with converging outer walls secured to the frame, a second U-shaped section, a fluid actuated cylinder carried by the frame and secured to the second U-shaped section for moving the latter in alignment with the inverted U-shaped section and an adjustable member secured to the frame and adapted to engage 35 the cylinder to limit the relative movement between the U-shaped sections.
7. An inner tube deflating device comprising a frame, a pair of telescoping U-shaped sections carried by the frame and provided with peripheral surfaces converging at an angle of approximately 12° with respect to the plane of the surface and means associated with the sections to actuate them. 40
- In witness whereof, I have hereunto 45 signed my name.

SIDNEY R. HARRINGTON.
